(57) **CLAIM**

The ornamental design for a data input machine, as shown and described.

DESCRIPTION

FIG. 1 is a perspective view of a data input machine showing our new design;

FIG. 2 is a top plan view thereof;

FIG. 3 is a front elevational view thereof;

FIG. 4 is a right side elevational view thereof;

FIG. 5 is a bottom plan view thereof; and,

FIG. 6 is VI-VI cross-sectional view with internal mechanism omitted therefrom.

The left side elevational view, which has a symmetrical relationship with the right side elevational view, is omitted herein.

The rear elevational view, which has a symmetrical relationship with the front elevational view, is omitted herein.
